UNITED STATES PATENT OFFICE.

THOMAS EDMUND HOLMES, OF GLASGOW, SCOTLAND.

STEAM-HYDRAULIC INTENSIFIER.

1,319,583.

Specification of Letters Patent.

Patented Oct. 21, 1919.

Application filed April 24, 1919. Serial No. 292,482.

To all whom it may concern:

Be it known that I, THOMAS EDMUND HOLMES, a subject of the King of Great Britain and Ireland, and a resident of Glasgow, Scotland, have invented certain new and useful Improvements in Steam-Hydraulic Intensifiers, of which the following is the specification.

When steam-hydraulic intensifier-operated forging presses and the like are used for rapidly repeated short-stroke operations, the piston of the steam cylinder gradually works toward the outer end of its stroke, that is to say, it does not return to the inner end of the stroke between each successive movement. This leads to great waste of steam.

The invention has for its object to obviate this disability and to reduce the consumption of steam to a minimum by the provision of means for insuring the definite return of the piston after each outward stroke.

According to the invention there is provided between the usual floating lever or hunting gear (conjointly operated from the moving piston of the intensifier and the controlling hand-lever) and the steam admission valve which it controls, a connection which is automatically broken (so disconnecting the steam from operation by the hand lever through the hunting gear) when the hunting gear overruns the valve, and is automatically reestablished when the intensifier piston returns to the commencement of its stroke. Thus the piston having performed a stroke, must of necessity be returned to its starting position before the connection to the steam valve is reestablished so that a fresh stroke may be made.

The means for performing these functions may consist, for example, of a detent normally engaged by the hunting gear controlled valve-operating lever and making connection between that lever and the valve, but which detent is so controlled by a weight, spring, or equivalent, that upon the lever moving to free itself, the detent is withdrawn. A second device operated from the moving piston so controls the detent against the action of the weight, spring, or equivalent, that the detent is reengaged with the valve operating lever upon return of the piston to the beginning of its stroke.

It is obvious that the carrying out of the invention as regards structural details may be very widely varied. An example purely

illustrative, and in no wise limitative is shown as applied to a normal type of intensifier valve gear in elevation on an accompanying sheet of explanatory drawings. 60

In this normal valve gear the spindles A¹, B¹ of the steam and exhaust valves A, B, are connected by links with a rocking lever C fulcrumed on a pin C¹ on the intensifier framing. An arm C² on this rocking lever 65 is connected by a link D¹ with a floating lever D, one end of which is pivoted on a bell-crank lever E pivoted on the framing, while the other end is operatively connected with a like bell-crank lever G. The bell- 70 crank lever G is connected by a link G¹ with the usual hand lever G². The bell-crank lever E is connected by a link E¹ with another bell-crank lever E² mounted on the framing and having an arm carrying a 75 roller E³ engaged by an inclined bar E⁴ moving with the piston rod E⁵ of the intensifier. The roller E³ is held in engagement with the inclined bar by a weight E⁶, and the whole forms the usual hunting gear. 80

The valve H, J, controlling the steam supply to the usual steam operated device for maneuvering the press-head or equivalent are controlled by a tappet lever H¹ moving with the hand lever G² and alternatively 85 engaging two tappets H², H³, on a rod H⁴ guided in the framing at one end and connected at its other end to a bell-crank lever J¹, connected by a link J² to a rocking lever J³, counterbalanced by a weight J⁴ and connected by links J⁵ to the valves H, J. 90

According to this example of the carrying out of the invention, instead of the steam admission valve A being connected by a simple link directly to the rocking lever C as is 95 usually the case, there is pivoted on the spindle A¹ of the steam-valve a detent lever K having a part K¹ adapted to be engaged by a pin C³ on the rocking lever C which lever has on its opposite end a pin C⁴ engaging a 100 slot (so as to provide a certain amount of "lost motion") in the link B², connecting the exhaust valve B with that lever. The detent lever K has a weight K² so applied to it as to tend to throw the detent part 105 K¹ out of engagement with the pin C³ and also has an arm on which is a pin K³ engaging a lost motion slot in a link L¹ connecting it to a lever L pivoted on the framing and which is connected by a second link 110 L² with a weight constrained bell-crank lever M connected in turn by a link M¹ through

a lost motion pin-and-slot device M^2 with a lever N fast on the same spindle as that a lever E on which is pivoted one end of the floating lever D .

5 Normally the weight K^2 tends to keep the detent K^1 of the lever K out of engagement with the pin C^3 , but the detent K^1 is of such a shape that so long as the pin C^3 exerts an upward pressure against it, it is held 10 in engagement. This upward pressure subsists so long as the hunting gear does not overrun the valve, but if it does, then immediately the weight K^2 withdraws the detent K^1 freeing the steam valve A which there- 15 upon closes. In order to get steam the operator must now return the hand-lever G^2 to the beginning of its stroke. When he approaches this point the steam piston returns to such a position and with it the inclined bar E^4 that the roller E^3 has taken 20 up the lost motion of the devices K^3 M^2 , and urged by its weight E^6 forces the detent K^1 back into engagement with the pin C^3 . The operator then again attains control 25 of steam.

What I claim is:—

1. In valve-gear for steam hydraulic intensifiers, a floating-lever or hunting-gear device controlling the steam admission and 30 exhaust valves, in combination with a connection between said device and the admis-

sion valve, means for automatically breaking the connection when the hunting-gear over-runs the valve, and for automatically reestablishing the connection when the steam piston returns to the beginning of its stroke. 35

2. The valve gear device forming the subject matter of claim 1 hereof, comprising a detent normally engaged by the hunting-gear-controlled valve-operating lever, making connection between that lever and the valve, a weight for controlling the detent, the detent being withdrawn when the lever moves to free itself, and devices operating 40 from the moving steam piston to reengage 45 the detent when the piston returns to the beginning of its stroke.

3. The valve gear device forming the subject matter of claim 1 hereof, comprising a 50 detent lever pivoted on the steam valve spindle and having a part adapted to be engaged by the co-acting valve-operating lever and so shaped that they normally hold one another in engagement, means tending to throw them out of engagement, and means 55 operated by the moving piston to reestablish said engagement only near the beginning of the piston stroke.

In testimony whereof I have signed my name to this specification.

THOMAS EDMUND HOLMES.
